UNITED STATES PATENT OFFICE.

FRITZ ACH, OF MANNHEIM, GERMANY, ASSIGNOR TO C. F. BOEHRINGER & SOEHNE, OF WALDHOF, GERMANY.

XANTHIN DERIVATIVE AND PROCESS OF MAKING SAME.

SPECIFICATION forming part of Letters Patent No. 631,757, dated August 22, 1899.

Application filed February 18, 1898. Serial No. 670,847. (Specimens.)

To all whom it may concern:

Be it known that I, FRITZ ACH, a citizen of the Empire of Germany, residing at Mannheim, in the Empire of Germany, have invented certain new and useful Improvements in the Art of Preparing Xanthins; and I do hereby declare the following to be a full, clear, and exact description of the invention, such as will enable others skilled in the art to which it appertains to make and use the same.

This invention relates to the manufacture of xanthins and their derivatives, and more particularly the preparation of this class of bodies from alkylized uric acids.

In order to define more exactly the ground which this invention occupies in the art, it is to be stated that a method has heretofore been found of obtaining the halogen derivatives of alkylized xanthins by the action of phosphorus-chlorid thereon, the xanthins, themselves, being then obtained by reducing the halogen derivatives. This method has been set forth in United States Patents to Emil Fischer, Nos. 569,489 and 569,490, dated October 13, 1896.

According to these patents such conversion was, however, only possible for such alkyl-uric acids as contained two alkyl groups in the alloxan ring and whose structure would be represented by the general formula:

adopting the nomenclature and system of numbering the carbon and nitrogen atoms of the purin nucleus which have been introduced by Emil Fischer and described in *Berichte der Deutschen Chemischen Gesellschaft*, Vol. 30, page 549—that is to say, only such alkyl-uric acids in which alkyl groups were bound to the molecule both at the position 1 and position 3 could according to that method be converted into xanthins. To proceed from mono-methyl-uric acids or from other dimethyl-uric acids to halogen or chlo-

roxanthins has hitherto been impossible. My investigations and experiments in this field have resulted in the discovery that all uric acids which have not been completely alkylized may be converted into the corresponding chloro-xanthins provided no alkyl group has been bound to the nitrogen atom in the position 9. In the latter case only chloro-purins would result. This discovery demonstrates that, contrary to the opinion hitherto entertained, it is immaterial for the preparation of xanthins from uric acids whether the nitrogen atoms 1 and 3—i. e., those in the alloxan ring—are alkylized or not. All that is material in this respect is that the nitrogen atom 9 be not alkylized. I have, moreover, ascertained as a result of my investigations that it is necessary to act upon the alkylized uric acid with phosphorus-oxy-chlorid alone in order to proceed to xanthins and that this result cannot be attained if the phosphorus-oxy-chlorid acts on the alkyl-uric acid in conjunction with phosphorus-penta-chlorid, for example. A comparison of the entirely and essentially different results obtained by acting on the same alkyl-uric acid first with phosphorus-oxy-chlorid together with phosphorus-penta-chlorid, according to the methods heretofore known, and then with phosphorus-oxy-chlorid alone, will serve admirably to emphasize the essence of the present invention. Thus if, for example, 7-monomethyl-uric acid is submitted to the joint action of phosphorus-oxy-chlorid and phosphorus-penta-chlorid the oxygen bound to the alloxan ring alone is replaced by chlorin, the resultant compound being 7-methyl-8-oxy-2-6-dichloropurin:

If, however, phosphorus-oxy-chlorid alone is caused to react on 7-monomethyl-uric acid, chlorin is substituted for the oxygen occupying the position 8, whereby the xanthin derivative 7-methyl-2-6-dioxy-8-chloropurin or 7-methyl-chloro-xanthin is obtained.

Again, if 3-7-dimethyl-uric acid be treated with phosphorus-oxy-chlorid together with phosphorus-penta-chlorid there is formed 3-7-dimethyl-2-8-dioxy-6-chloropurin, as shown in *Berichte der Deutschen Chemischen Gesellschaft*, Vol. 28, page 2480, and Vol. 30, page 554:

If, on the other hand, the phosphorus-oxy-chlorid alone is caused to act upon the 3-7-dimethyl-uric acid, substitution of chlorin will again take place in the position 8 instead of in the alloxan ring, the chloro-xanthin, 3-7-dimethyl-2-6-dioxy-8-chloropurin or chlorotheobromin being formed:

I have found that the same result is obtained with other alkyl-uric acids, and, in general, my invention shows that the use of phosphorus-oxy-chlorid alone results in the production of chloro-xanthins when acting upon alkyl-uric acids which have no alkyl group bound to the N occupying the position 9, while the treatment of such uric acids with both phosphorus-penta-chlorid and the oxy-chlorid would result in chloropurins, which are not xanthin derivatives.

According to my observations, intermediate products, apparently containing phosphorus and chlorin, are at first formed when phosphorus-oxy-chlorid reacts upon alkylized uric acids, these intermediate bodies being subsequently changed into chloroxanthins by treatment with suitable means, such as alcohol or water, while phosphoric acid and hydrochloric acid are split off.

The chloroxanthins obtained under my invention are converted into higher alkylized products by employing the alkylizing methods which are in use in connection with the uric acid and xanthin series. Thus, for example, chloro-theobromin may be obtained from 3-methyl-chloroxanthin on further methylation, the chloro-theobromin being in turn readily susceptible of conversion into chloro-caffein by the same methods.

The chloro-xanthins are converted into the corresponding xanthins by reducing methods.

It is to be noted that under my invention other alkyl radicals than the methyl group may be introduced into the xanthin-molecule. Thus the 3-methyl-chloro-xanthin is readily converted into 3-methyl-1-7-diethyl-chloro-xanthin by introducing the ethyl radical into the former.

For the purposes of my invention it is unimportant whether the lower chloro-xanthins are first alkylized and then reduced, or vice versa. In both ways I may proceed to the higher alkylized xanthins, such as caffein.

My invention, whose object is to obtain xanthins from uric acids, accordingly, broadly considered, consists in submitting alkalized uric acids, which, however, have no alkyl group at the position 9 to the action of phosphorus-oxy-chlorid. The said invention, moreover, consists in the subsequent reduction and alkalization of the resultant compounds, and, moreover, in the special products and subprocesses, all as will be herein-after specified, and pointed out in the claims hereunto annexed.

I will now proceed to fully disclose my invention for those skilled in the art by giving in detail a number of examples embodying what I consider the best manner of carrying said invention into effect.

I. *Preparation of Halogen Derivatives of Alkalized Xanthins from the Corresponding Uric Acids.*

1. *Preparation of 3-methyl-chloro-xanthin from 3-methyl-uric acid.*—One part of anhydrous 3-methyl-uric acid is added to five parts, by volume, of phosphorus-oxy-chlorid and heated under pressure—e. g., in a digester—to from 130° to 140° centigrade, and maintained at this temperature for from three to four hours, the mass being steadily agitated. The resulting clear reddish-brown solution is then evaporated *in vacuo* for the purpose of completely removing the phosphorus-oxy-chlorid. The brownish residue, which has a tough varnish-like consistency, is thereupon brought into solution by boiling the same with about five times its quantity of alcohol or water. The alcohol solution, which at first is clear, but soon becomes turbid on account of the precipitation of granular crystalline methyl-chloro-xanthin, is boiled for from two to three hours in a reflux-condenser and then allowed to cool. Upon then filtering the methyl-chloro-xanthin remains on the filter as a yellow granular crystalline mass. The filtrate is then evaporated, whereby a second crystallization ensues, resulting in a further yield of the above product—methyl-chloro-xanthin. The crude product so obtained is brought into solution with dilute alkali, such as two per cent. potash-lye, treated with animal charcoal or other decolorizing agent, and finally precipitated with dilute sulfuric acid. On cooling, the new

compound is obtained in the form of yellow-hued coarse crystals, from whose analysis are obtained figures which show the formula of this compound to be $C_6H_5N_4O_2Cl + H_2O$.
5 Its structural formula is found to be:

such formula being established by the fact of 15 the ready conversion of this compound into chloro-caffein. (See under II 1a.) I therefore designate this new compound as 3-methylchloro-xanthin or 3-methyl-8-chloro-xanthin. The tenaciously-adhering yellow tint, 20 which is very difficult of removal, has no influence on the percentage composition of the product.

Absolute decoloration of the methyl-chloro-xanthin may be attained by thoroughly boiling 25 it with a large quantity (thirty parts to one part of the methyl-chloro-xanthin) of acetone. The xanthin is thereby gradually brought into solution, while the adhering coloring matter remains undissolved. Upon 30 cooling after such solution is effected the methyl-chloro-xanthin crystallizes in anhydrous fine colorless shining foliated crystals or scales.

3-methyl-chloro-xanthin is soluble in about 35 two hundred and fifty parts boiling water, and on cooling the solution slowly the same crystallizes therefrom in coarse needles, which under the microscope are found to be elongated flat prisms and which contain one molecule of water of crystallization. This water of crystallization escapes on protracted heating at 120° centigrade. It is difficult of solution in boiling alcohol, in acetone, acetic ether, benzene, or chloroform, readily soluble 40 in dilute alkalies, in ammonia and soda, or potash solutions. It is equally soluble in concentrated sulfuric acid and fuming hydrochloric acid. From a solution in the latter the original product is precipitated by 45 water on standing for some time. Heated with chlorin water or with dilute nitric acid it gives a strong murexid reaction. An ammoniacal solution of the same added to an ammoniacal silver solution yields a gelatinous silver-salt which remains unchanged on 50 boiling.

3-methyl-chloroxanthin has no melting point; but on being rapidly heated it begins to turn yellow at 320° centigrade, and at about 55 345° centigrade it decomposes with effervescence.

2. Preparation of 7-methyl-2-6-dioxy-8-chloropurin or chloro-heteroxanthin from 7-monomethyl-uric acid.—One part, by weight, of dried and finely-powdered 7-mono-methyl-uric acid is added to ten parts, by volume, of phosphorus-oxy-chlorid and boiled for from

20 twenty-four to thirty hours in a reflux-condenser. This treatment results in the solution of methyl-uric acid, a clear slightly-colored liquor being formed. This liquor is evaporated ⁷⁰ in *vacuo*, and the tough, varnish-like residue is taken up with warm alcohol. After boiling such solution a short time the chloro-heteroxanthin is thrown out in the ⁷⁵ form of a colorless crystalline mass, which is separated by filtration. This product is not quite pure, but is contaminated with some unchanged methyl-uric acid, which may be removed by boiling with much acetone, which ⁸⁰ dissolves the chloro-heteroxanthin but not the methyl-uric acid. The acetone solution is then evaporated, and the resulting crystalline residue is taken up with dilute ammonia, treated with decolorizing carbon, and precipitated with dilute sulfuric acid. The ⁸⁵ 7-methyl-chloroxanthin or chloro-heteroxanthin is thereby obtained in the form of colorless short prismatic crystals which give figures corresponding to the formula $C_6H_5N_4$ ⁹⁰ O_2Cl . Its structural formula is

as is shown by its conversion into chloro-caffein. (See II 1b.)

The chloro-heteroxanthin or 7-methyl-2-6-dioxy-8-chloro-purin is formed about according to the equation:

That this new product is a xanthin derivative is also corroborated by the fact that it ¹²⁰ gives the murexid test with chlorin-water or dilute nitric acid. From boiling water, in which it is moderately soluble, it crystallizes in short needles which are frequently aggregated in bunches. It is soluble with difficulty in alcohol and acetone and with very great difficulty in benzene or chloroform. It is readily taken up by dilute alkalies, ammonia, and soda or potash (carbonates) solutions. An ammoniacal solution of the same, ¹²⁵ added to an ammoniacal silver solution, gives rise to a colorless silver-salt consisting of fine needles, which salt remains unchanged on boiling.

Chloro-heteroxanthin has no melting-point; but on being heated rapidly it becomes yellow at about 300° centigrade and is decomposed at about 340° centigrade, the decomposition being attended by dark-brown coloration and effervescence.

3. Preparation of 3-7-dimethyl-2-6-dioxy-8-chloro-purin or chloro-theobromin from 3-7-dimethyl-uric acid.—One part, by weight, of 3-7-dimethyl-uric acid which has been reduced to the finest possible powder is added to five parts, by volume, of phosphorus-oxy-chlorid and the whole boiled with reflux until a clear solution is formed. This requires about twenty hours. From the resulting liquid, which is slightly colored, the unchanged phosphorus-oxy-chlorid is distilled off *in vacuo* and the residue is dissolved with alcohol. The solution is then boiled. After a short time the chloro-theobromin which has been formed begins to crystallize out of the solution. The reaction takes place about according to the equation:

The crystals are then separated by filtration and dissolved in dilute alkali and treated with carbon for decoloration, whereupon the chloro-theobromin is thrown out by dilute sulfuric acid. The colorless product so obtained has the composition indicated by the formula $\text{C}_7\text{H}_7\text{N}_4\text{O}_2\text{Cl}$ and the structure,

wherefore I term it 3-7-dimethyl-2-6-dioxy-8-chloropurin or 3-7-dimethyl-8-chloroxanthin or 8-chlorotheobromin. The above structure is established by the ready and smooth conversion of this new compound into chloro-caffein set forth under II 1c.

60 Chlorotheobromin heated with chlorin-water or with dilute nitric acid gives the murexid test. On heating the same rapidly it melts at about 292° to 293° centigrade to a slightly-colored liquid, which soon congeals to a crystalline mass on cooling. It dissolves in about two hundred and fifty parts of water on boiling. From such aqueous solution

it is thrown out in the form of colorless vitreous shining short prisms on cooling slowly and in the form of fine needles aggregated in bunches on cooling rapidly. It is only difficultly soluble in boiling alcohol. On the other hand it is readily soluble in dilute alkalies and dilute warm ammonia. From a solution of the same in soda-lye its sodium-salt is rapidly thrown out in the form of fine acicular crystals by concentrated soda-lye. If an ammoniacal solution of the same be added to an ammoniacal silver solution and the ammonia be removed by boiling, a gelatinous colorless silver-salt of the chloro-theobromin is thrown out.

II. Conversion of the Above Halogen Derivatives into Higher Alkylized Products.

1. Preparation of chloro-caffein. (a) From 3-methyl-chloro-xanthin.—One part, by weight, of 3-methyl-chloro-xanthin, which has been described hereinabove, is brought into solution with five and four-tenth parts, 90 by volume, of double-normal potash-lye (potassium-hydrate) and equal parts of water, and after one and one-half parts, by weight, of methyl-iodid have been added thereto the whole is heated to 90° centigrade in the pressure-tube and maintained at this temperature for from two to three hours, the mass being constantly agitated. The same is then allowed to cool, when the greater portion of the chloro-caffein which has been formed is thrown out in the form of fine needles. The balance of the chloro-caffein is obtained by extraction from the lyes, which have previously been rendered slightly alkaline by a suitable solvent, such as chloroform, for example. The formation of chloro-caffein takes place according the equation:

The actual amount of chloro-caffein obtained corresponds to the theoretical yield. It is fully purified on once recrystallizing from water and has all of the characteristic properties found for chlorocaffein by Emil Fischer, (*Annalen*, Vol. 215, page 263.)

(b.) From 7-methyl-chloroxanthin.—Three parts, by weight, of 7-methyl-chloroxanthin or chloro-heteroxanthin, which has been hereinbefore described, are dissolved in eighteen parts, by volume, double-normal caustic-potash lye (potassium-hydrate) and thirty-six

parts, by volume, of water, and after adding thereto five parts, by weight, of methyl-iodid the same is heated to 90° centigrade in the pressure-tube, this temperature being maintained for two and one-half hours and the mass being constantly agitated. After allowing the same to cool the resultant chloro-caffein will be found to exist in the tube in the form of a paste or pulp. It is isolated as set forth under (a).

The conversion of chloro-heteroxanthin or 7-methyl-chloroxanthin into chloro-caffein takes place according to the equation:

In this case, also, the practical yield is equivalent to the theoretical, and the chloro-caffein is obtained pure.

(c.) *From chloro-theobromin.*—The same treatment applied to dimethyl-chloroxanthins, such as chloro-theobromin, which is 3-7-dimethyl-2-6-dioxy-8-chloropurin or 3-7-dimethyl-8-chloroxanthin, will again result in the trimethyl-chloroxanthin or chloro-caffein.

If two parts, by weight, of the chloro-theobromin which has been described under head I 3 be dissolved in seven volumes of double-normal potash-lye (potassium-hydrate) and seven volumes of water and heated to 90° centigrade under pressure, together with one and one-half parts of methyl-iodid, this temperature being maintained for three hours and the liquid constantly agitated, the formation of chloro-caffein will take place. The greater portion of the same is thrown out in the form of fine acicular crystals after cooling, while the remainder is obtained by extraction with a suitable vehicle, such as chloroform. The following equation explains the reaction which takes place:

Here, again, the theoretical and practical yield are identical.

2. *Preparation of chlorotheobromin from 3-methyl-chloroxanthin.*—Six parts, by weight, of 3-methyl-chloroxanthin are dissolved in eighteen parts, by volume, of double-normal potash-lye (potassium-hydrate solution) and thirty parts, by volume, of water. There are then added to the solution seven and two-tenths parts of methyl-sulfate of potassium, and the whole is then heated to from 140° to 150° centigrade under pressure—*e.g.*, in a digester—this temperature being maintained for from four to five hours and the mass constantly agitated. Upon cooling the chlorotheobromin 3-7-dimethyl-8-chloroxanthin is separated out of the solution in the form of coarse yellowish-brown granular crystals. It is purified by redissolving and crystallizing out of alkalies, such as potash-lye, and possesses all of the characteristic properties, as well as the melting-point, of the chlorotheobromin described under I 3. The reaction which results in its formation proceeds according to the equation:

3. *Preparation of 3-methyl-1-7-diethyl-2-6-dioxy-8-chloropurin from 3-methyl-chloroxanthin.*—Four parts, by weight, of 3-methyl-chloroxanthin are dissolved in twenty-three parts, by volume, of double-normal potash-lye (potassium-hydrate solution) and diluted with twenty parts, by volume, of alcohol. Six and one-half parts, by weight, of ethyl-iodid are then added, and the whole is boiled for from three to four hours in a reflux-condenser. The mass is then allowed to cool, when it solidifies in the form of a pulp or fine felted needles. These are then separated by filtration, redissolved in boiling water, and recrystallized therefrom. The fine acicular crystals so obtained have the composition indicated by the formula $\text{C}_{10}\text{H}_{18}\text{N}_4\text{O}_2\text{Cl}$ or, structurally expressed,

The reaction to which the formation of the

new compound is due proceeds according to the equation:

This new compound, with chlorin-water, gives a strong murexid reaction. Its melting-point is 136° centigrade. It is moderately soluble in boiling and difficultly soluble in cold water. It dissolves readily in hot alcohol and in cold acetone or chloroform. It is also readily soluble in fuming hydrochloric acid, being precipitated from such solution by water. It will be noted that its structure closely resembles that of chloro-caffein, the only difference being that in lieu of the methyl groups in the positions 1 and 7 in the latter compound it has substituted ethyl groups.

III. Reduction of the Halogen Derivatives to the Corresponding Xanthins.

45 1. Preparation of 3-methyl-2-6-dioxypurin or 3-methyl-xanthin from 3-methyl-chloro-xanthin.—If one part, by weight, of 3-methyl-chloro-xanthin, described under head I¹, is heated with ten times its weight of fuming
50 hydriodic acid, a gradual solution and reduction of the chloro compound takes place, which is attended by a liberation of iodin. The heating (at a temperature of from 90° to 100° centigrade) is continued and phosphonium-
55 iodid added from time to time until a clear colorless solution is formed. The solution is then evaporated, whereby the iodohydrate of this new base is thrown out in the form of coarse colorless prismatic crystals. After the
60 evaporation has been continued to complete dryness the residue is taken up with water, which causes the iodohydrate to be decomposed and the methyl-xanthin to be isolated in the form of fine colorless needles. The
65 practical yield corresponds to the theoretical. The base is recrystallized from boiling water and so obtained in the form of fine shining

needles. Its formula is $C_6H_6N_4O_2$ or, structurally:

This new base as a xanthin gives a strong 95 murexid reaction only with chlorin-water, while if it is evaporated together with moderately-concentrated nitric acid it yields a slightly-colored residue, which is dissolved in strong potash-lye, and thus forms a clear deep-yellow solution. It requires from three hundred to three hundred and thirty parts of boiling water for solution, but is readily soluble in dilute alkalies and ammonia and also in concentrated sulfuric or hydrochloric acid. 100 105 An ammoniacal solution of the same when added to a solution of nitrate of silver gives rise to a colorless silver salt consisting of fine needles. This silver salt dissolves in a large excess of ammonia on heating and remains unchanged on boiling. If a solution of the 3-methyl-xanthin in dilute nitric acid is added to nitrate of silver, a double salt, consisting of coarse acicular crystals intermeshed in the form of bunches, is thrown out. 110 115 This double salt is readily soluble in hot water.

3-methyl-xanthin has no melting-point. When heated above 360° centigrade, it begins to become yellow, and on raising the temperature above 400° centigrade it is decomposed without melting. 120

This new body differs from the compound, heteroxanthin, described in Patents Nos. 617,985 and 617,986, dated January 17, 1899, ¹²⁵ only in the location of the methyl group. While in the latter compound this group is in the position 7, in the present compound it occupies the position 3.

2. Preparation of 7-methyl-2,6-dioxy-purin or heteroxanthin from 7-methyl-8-chloro-xanthin.—If one part, by weight, of 7-methyl-chloro-xanthin, (described under I²), be heated on the water-bath, together with eight times

its weight of fuming hydriodic acid of the specific gravity 1.96, phosphonium-iodid being added from time to time to the mixture, a clear colorless solution is soon formed, whereby the end of the reaction is indicated. The reaction proceeds according to the equation:

15 The resulting liquid is evaporated to dryness, and the residue is repeatedly dissolved in water and evaporated to completely remove the hydriodic acid. The crystalline residue 20 is then suspended in about twenty parts of hot water and soda-lye (sodium hydrate) is added until complete solution is effected, when it is allowed to cool. On cooling, the characteristic difficultly-soluble sodium salt 25 of heteroxanthin is thrown out in the form of coarse colorless crystals. This reaction is expressed in the equation:

30 The heteroxanthin may then be liberated from the sodium salt by dissolving in hot water, 45 supersaturating with acetic acid and separating by filtration. The heteroxanthin so obtained possesses all the characteristic properties enumerated in Emil Fischer's patent, No. 618,045, dated January 17, 1899.

50 *3. Preparation of 3-7-dimethyl-2-6-dioxy-purin or theobromin from chloro-theobromin.*—If one part, by weight, of chloro-theobromin or 3-7-dimethyl-2-6-dioxy-8-chloropurin, which has been described under head I³, be heated on the water-bath with eight times its weight of fuming hydriodic acid of the specific gravity 1.96, one-half (about) part of phosphonium-iodid being added, a colorless clear solution will be obtained after the 55 lapse of from fifteen to twenty minutes. This indicates that the reduction of the chloro-theobromin has been completed. The liquid is then evaporated to complete dryness to eliminate the surplus of hydriodic acid. The 65 colorless crystalline residue is then taken up with water, whereby the said residue is first dissolved. After a short time, however, the

formation of colorless indistinct crystals ensues. These are redissolved and recrystallized from boiling water, and they possess all 70 the characteristic properties of theobromin. They crystallize in small colorless prisms, melt at about 345° centigrade without decomposition, and when dissolved in nitric acid they unite with nitrate of silver to form the 75 double salt, which forms fine needles. The reducing reaction whereby the theobromin is formed from the chloro-theobromin is elucidated in the equation:

80 The theoretical and practical yields of theobromin are identical.

4. *Preparation of 3-methyl-1-7-diethyl-2-8-dioxy-purin.*—This new body is obtained by reduction of 3-methyl-1-7-diethyl-2-6-dioxy-8-chloropurin or 3-methyl-1-7-diethyl-8-chloroxanthin, which has been described under head II³. If one part, by weight, of this chloroxanthin be heated with ten parts, by weight, of fuming hydriodic acid to 90° centigrade, solution is speedily effected. The heating is then continued on a boiling water-bath so long until with the addition of phosphonium-iodid in sufficient quantity to take up the liberated iodin a clear solution is formed. This solution is then evaporated to dryness and the crystalline residue is taken up with water and supersaturated with alkali. Through this treatment the new base separates as a colorless oil, which very soon 100 congeals, forming fine acicular crystals. The base is then extracted with a suitable vehicle, such as chloroform or ether, whereupon the extract is evaporated and the colorless residue recrystallized from benzene. From the 105 benzene solution, to which ligroin is preferably added, the methyl-diethyl-dioxypurin crystallizes in the form of splendidly-developed vitreous colorless prisms, whose analysis gives figures which correspond well to the 110 formula C₁₀H₁₄N₄O₂. The structural formula 115 of the base is

The reducing process is expressed in the equation:

20 As a xanthin this new body with chlorin-water gives a strong murexid reaction. It melts at from 127° to 128° centigrade. It is readily soluble in water, alcohol, chloroform, benzene, ether, and concentrated hydrochloric or sulfuric acid. From an aqueous solution this mass is precipitated by concentrated alkaline lyes as a colorless oil which soon solidifies to a crystalline mass.

30 **IV. Alkylizing Subsequent to Reducing the Halogen Derivatives.**

35 *Alkylization of 3-methyl-xanthin.*—In preparing the higher alkylized xanthins from the chloro-xanthins described under I it is not indispensably necessary to first further alkylize the chloro-xanthins and then to reduce such higher alkylized products; but the order of these steps may be equally well reversed.

40 *40* by first reducing the chloro-xanthins and then alkylizing the reduced products. My invention therefore, broadly considered, consists in reducing and alkylizing the chloro-xanthins irrespective of the order of these 45 two steps.

1. *Preparation of 3-7-dimethyl-xanthin (theobromin) from 3-methyl-xanthin.*—Seven parts, by weight, of 3-methyl-xanthin are dissolved in twenty-six parts, by volume, of potash-lye (potassium-hydrate solution) of double normal strength, and fifty parts, by volume, of water, and, after adding thereto eight parts, by weight, of methyl-iodid, heated to 80° centigrade and maintained at this temperature for three hours while constantly agitating the mass. After cooling, the liquid will be found to be filled with a pulpy mass of colorless crystals. The mother-liquor is removed from these crystals by filtration or 55 otherwise, and they are then redissolved in and recrystallized from boiling water. The colorless crystals so obtained possess all of the characteristic properties of natural theobromin. The reaction takes place according 60 to the equation:

80 *2. Preparation of 1-3-7-trimethyl-xanthin (caffein) from 3-methyl-xanthin.*—One part, by weight, of 3-methyl-xanthin is dissolved in 6.8 parts, by volume, of double normal potash-lye (potassium-hydrate solution) and fifteen parts, by volume, of water and heated to 80° centigrade, together with two parts, by weight, of methyl-iodid, this temperature being maintained for three hours and the mass constantly agitated. The clear liquid so obtained is highly evaporated and then extracted with chloroform. The fine acicular crystals resulting from this treatment have the melting-point 232° centigrade and all of the other properties of caffein. The reaction takes place according to the equation:

The yield in caffein obtained corresponds to the theoretical yield.

95 It will be seen from a review of the above that my invention, broadly considered, consists in treating an alkyl-uric acid, having no alkyl in the position 9, with phosphorus-oxy-chlorid alone, and also in the process of alkylizing such of the chloro-xanthins resulting from such treatment, with or without subsequent reduction of the alkylized chloro-xanthin. It will be observed, moreover, that it is immaterial whether the alkylization precedes or follows the reduction of the chloro-xanthin, and that alkylization with subsequent reduction is to be considered as an equivalent of reduction of the chloro-xanthin with subsequent alkylization.

100 Although I have herein described the new compounds, 7-methyl-chloro-xanthin and 3-

7-dimethyl-chloro-xanthin, and the methods of preparing the same and also of reducing and alkylizing them in illustration of my invention, I do not herein claim these new compounds nor the specific methods involved in their preparation, since these form the subjects-matter of and are claimed in my applications, Serial Nos. 670,848 and 678,849, filed concurrently herewith, (Cases K and L.) Nor do I herein claim the new compound, 3-methyl-xanthin (having the methyl group in the position 3) or the specific process of preparing the same, although they have been herein described in illustration of my invention, broadly considered, nor specifically the process of first reducing and then alkylizing the 3-methyl-chloro-xanthin, since all of these are claimed in my application, Serial No. 672,543, filed March 4, 1898. The invention covered in the present application, however, consists in the method broadly of alkylizing and reducing the 3-methyl-chloro-xanthin when the same is considered irrespective of the order of these two steps. Finally I do not herein claim the compound 3-methyl-1-7-diethyl-2-6-dioxopurin or 3-methyl-1-7-diethyl-xanthin or the specific methods of preparing the same, since these form the subject-matter of and are claimed in my application, Serial No. 724,838, filed July 22, 1899.

What I claim, and desire to secure by Letters Patent of the United States, is—

1. The process in the art of preparing xanthins which consists in acting upon alkylized uric acids having no alkyl group in the position 9 with phosphorus-oxy-chlorid.

2. In the art of preparing xanthins the process which consists in adding phosphorus-oxy-chlorid to an alkyl-uric acid having no alkyl group in the position 9 and heating the mixture.

3. In the art of preparing xanthins the process which consists in adding phosphorus-oxy-chlorid to an alkyl-uric acid having no alkyl group in the position 9 and heating the mixture, then evaporating the resulting solution to remove surplus of phosphorus-oxy-chlorid, then dissolving the residue after evaporation with alcohol or water and boiling such solution.

4. In the art of preparing xanthins the process which consists in adding phosphorus-oxy-chlorid to an alkyl-uric acid having no alkyl group in the position 9, heating the mixture, then evaporating the resulting solution to remove surplus of phosphorus-oxy-chlorid, then dissolving the residue after evaporation with alcohol or water and boiling such solution, then allowing the solution to cool and filtering to evaporate the crystalline alkyl-chloro-xanthin from the mother-liquor.

5. The process which consists in treating

an alkyl-uric acid, having no alkyl group in the position 9, with phosphorus-oxy-chlorid, and then after isolating the resultant chloro- 65 xanthin, alkylizing the same.

6. The process which consists in treating an alkyl-uric acid, having no alkyl group in the position 9, with phosphorus-oxy-chlorid and then after isolating the resultant compound, submitting the same to alkylization and reduction.

7. The process which consists in treating 3-methyl- uric acid with phosphorus-oxy- chlorid.

8. The process which consists in heating 3-methyl-uric acid with phosphorus-oxy-chlorid under pressure, then evaporating the resultant clear solution to recover the excess of oxy-chlorid, then boiling the residue in alcohol, then cooling and filtering, all substantially in the proportions and under the conditions set forth.

9. The process which consists in heating 3-methyl-uric acid with phosphorus-oxy-chlorid under pressure, then evaporating the resultant clear solution to recover the excess of oxy-chlorid, then boiling the residue in alcohol, then cooling and filtering, then dissolving the crystalline crude product in alkali 90 to which a decolorizing agent is added, and precipitating with acid, all substantially in the proportions and under the conditions set forth.

10. As a new chemical compound, 3-methyl- 95 chloro-xanthin, which has the formula hereinabove given, is difficult of solution in boiling alcohol, in aceton, acetic ether, benzene or chloroform, but readily soluble in dilute alkalies, in ammonia soda or potash solutions, 100 soluble in concentrated sulfuric or fuming hydrochloric acid, has no melting-point, but on being rapidly heated, begins to turn yellow at about 320°, centigrade, decomposing at about 345°, centigrade, with effervescence, 105 and crystallizes from boiling water on cooling in coarse needles, containing one molecule of water of crystallization, which escapes on heating at 120° centigrade.

11. The process which consists in submitting 3-alkyl-chloro-xanthin to the action of reducing and of alkylizing agents.

12. The process which consists in submitting 3-methyl-chloro-xanthin to the action of reducing and of methylating agents.

13. The process which consists in submitting 3-methyl-chloro-xanthin to the action of a methylating agent.

In testimony whereof I affix my signature in presence of two witnesses.

FRITZ ACH.

Witnesses:
